FIG. 5.

FIG. 6.

FIG. 7.

Inventor:—
Clarence C. Chrisman
By Martin G. Smith,
Atty.

UNITED STATES PATENT OFFICE.

CLARENCE C. CHRISMAN, OF MARTINSBURG, MISSOURI.

PUMP SPOUT.

Application filed June 12, 1923. Serial No. 644,878.

To all whom it may concern:

Be it known that I, CLARENCE C. CHRISMAN, a citizen of the United States, residing at Martinsburg, in the county of Audrain and State of Missouri, have invented certain new and useful Improvements in Pump Spouts, of which the following is a specification.

My invention relates to a pump spout, 10 the principal object of the invention being to provide a relatively simple and practical structure that is under the ready control of the operator of the pump and which will discharge the pumped water into a receptacle or divert said pumped water back into the well or receptacle from whence it was lifted by the pumping means.

It will be understood that if water stands 20 in the pipes of a pump, it becomes stale, and it is the purpose of my invention to provide a simple and efficient means which will permit the pumping of the water that has been standing in the pipes of a pump, back into the well or receptacle, thus saving 25 said water and also purifying it as a result of its passage through the air.

Where my device is used, the operator 30 may, after pumping a sufficient amount of water back into the well or receptacle, actuate a valve-like device so that the comparatively cool, fresh water that is drawn from the well or receptacle will pass through a screened opening in the pump spout and discharge into a suitable receptacle positioned beneath said spout. The 35 use of strainer in the mouth or discharge opening of the spout prevents any foreign substance or objects from being delivered with the pumped water into the receptacle 40 suspended from, or positioned beneath the spout.

A further object of my invention is to 45 provide an attachment for the spouts of pumps that are already installed, and which attachment may be readily manipulated so as to permit water to discharge from the spout, or to be returned to the well or receptacle with which the pump is associated.

With the foregoing and other objects in 50 view, my invention consists in certain novel features of construction and arrangement of parts that will be hereinafter more fully

described and claimed and illustrated in the accompanying drawings in which:

Fig. 1 is a perspective view of a pump 55 spout of my improved construction.

Fig. 2 is a vertical section taken on the line 2--2 of Fig. 1.

Fig. 3 is a sectional view taken vertically through the end of my improved spout 60 and showing the valve in position so as to cause the pumped water to be returned to the well or receptacle with which the pump is associated.

Fig. 4 is a horizontal section taken on the line 4--4 of Fig. 2.

Fig. 5 is a vertical section taken through the center of an attachment that embodies the principles of my invention, and which may be detachably connected to an ordinary 70 metal pump spout.

Fig. 6 is a sectional view similar to Fig. 5 and showing the attachment adjusted so as to cause the pumped water to return to the well.

Fig. 7 is a vertical section taken through the center of a modified form of a pump spout embodying my invention.

Referring by numerals to the accompanying drawings, and particularly to the construction illustrated in Figs. 1 to 4, inclusive, 10-10 designate mating parts of the spout, which parts are preferably formed of metal, either cast or stamped, and the dividing line between said parts being vertically disposed and extending lengthwise of the completed spout. The two parts thus constructed are securely connected to each other, preferably by means of bolts 11 that pass through suitably located lugs 12, and the rear ends of the parts 10 are provided with flanges 13 that may be secured in any suitable manner to the pump housing H.

A horizontally disposed partition 14 extends lengthwise of the spout at a point midway between its top and bottom walls, said partition terminating a short distance from the front end of the spout.

The lower portion of the wall at the front end of the spout is cut away to form a 100 discharge opening 15, and the latter is located directly in front of the chamber 16 that is below the partition 14. This chamber 16 forms a return duct, or passageway,

through which the pumped water returns to the well or receptacle and the chamber 17, above the partition 14, constitutes the duct through which the pumped water flows outwardly through the spout.

The inner faces of the side walls of the spout directly in front of and below the partition 14 are provided with substantially triangular recesses 18, through which are adapted to travel the side edges of a substantially rectangular plate 19 and which latter performs the functions of a valve to direct the flow of the water through the forward portion of the spout.

Formed integral with and projecting outwardly from the lower portions of the ends of this plate are trunnions 20, that are journaled in suitable bearings in the lower portions of the side walls of the spout and at the lower ends of the recesses 18. Thus the valve plate 19 is mounted so that it may swing freely through the space between the recesses 18 so as to direct the pumped water from duct 17 into duct 16, or direct said pumped water downwardly from the forward end of the duct 17 to the outlet or discharge opening 15.

The upper edge of valve plate 19 is preferably bevelled so that it may fit snugly beneath the correspondingly bevelled forward edge of partition 14 when in position to direct the water out through opening 15, and the edge of the top wall of the spout directly above the opening 15 is provided with a lip 21 against which the upper edge of plate 19 bears when it is in position to redirect the pumped water back through duct 16.

The ends of valve plate 19 are formed so that they fit snugly against the inclined shoulders formed at the ends of the recesses 18, and which arrangement provides substantially water-tight joints between the valve plate and the side walls of the spout.

Formed integral with the lower end of plate 19 is the lower end of a plate 22 that is disposed at an angle of approximately sixty degrees relative to said plate 19, said plate 22 projecting through the discharge opening 15 and being provided with an opening 23 in which is arranged a screen 24, preferably a section of wire netting of relatively small mesh.

When it is desired to pump the water that has been standing in the pump pipes back into the well or receptacle with which the pump is associated, the valve at the forward end of the spout is shifted so that plate 19 occupies the inclined position, as shown in Fig. 3, with its upper edge bearing against lip 21, and as the pump is operated, the pumped water that discharges into and through duct 17 will pass through the forward end of said duct into and through the duct 16, and it will discharge from the rear

end thereof back into the well or receptacle. This pumping of the water that has been standing in the pump pipes will tend to aerate it, and when a sufficient amount of water is thus pumped and returned to the well, the valve is manipulated so as to swing plate 19 into an inclined position as illustrated in Fig. 2 with its upper edge bearing against the front end partition 14.

When so positioned, plate 22 occupies an inclined position between the forward end of duct 17 and the outlet opening 15, and the pumped water will, after passing through the duct 17, pass through the screen 24, and then discharge from opening 15 into a receptacle that may be suspended from or positioned beneath the forward end of the spout.

The construction illustrated in Figs. 5 and 6, and which is designed to be associated with ordinary metal pump spouts, includes a housing 25, preferably formed of sheet metal, and which is provided in its upper wall and near its forward end with an opening 26 that is surrounded by an upwardly projecting flange 27. This flange receives the lower end of the usual pump spout S, and the device may be secured to said spout by means of a wire 28 that passes around said flange.

Formed in the bottom of the housing 25 and directly opposite to the opening 26, is a discharge opening 29.

The rear end of housing 25 may extend through the wall W of the pump at a point directly below spout S or, if desired, a return pipe 30, shown by dotted lines in Fig. 5, may extend from the rear portion of the housing downwardly through the platform supports of the pump and which forms a cover for the well.

Arranged for sliding movement in the forward portion of the housing 25 is a substantially channel-shaped member 31 having in its bottom plate an opening 32 that is covered by a section 33 of wire screen, and arranged within said member 31 and to the rear of this screened opening is a vertically disposed partition 34.

When this form of the device is adjusted to permit the pumped water to discharge into a receptacle placed below the pump spout, member 31 is moved into the housing 25 so that the screened opening 32 registers with discharge opening 29, and when so positioned, partition 34 is located at a point to the rear of opening 26. Thus, as the pump is operated, the water from spout S passes through opening 26, thence through the chamber within the device in front of partition 34, and thence through the screened opening 32 and discharge opening 29.

When this device is adjusted to effect a return of the pumped water into the well or

receptacle with which it is associated, member 31 is drawn outward to the position as illustrated in Fig. 6. When member 31 is thus adjusted, partition 34 occupies a position in front of the opening 26 and discharge opening 29 is closed by the imperforate rear portion of said member 31.

With the parts thus positioned, the pumped water discharges from the forward end of spout S into the open-topped rear portion of member 31, and passes back through housing 25 to the well or receptacle with which the pump is associated.

In the modification illustrated in Fig. 7, a hollow cylindrical valve plug 35 is arranged for rotation within a vertically disposed chamber at the forward end of the pump spout and which latter is provided with ducts 36 and 37 that correspond with the ducts 16 and 17 and said spout being also provided with an outlet 38 that is disposed opposite to the duct 37. The rotary valve plug 35 is provided on one side with spouts 39 and 40 that are adapted to register, respectively, with ducts 36 and 37, and formed in the upper portion of said block, directly opposite port 39 is a second port 41.

By giving plug 35 a half turn, the pumped water passing through duct 36 will discharge from outlet 38, or said pumped water may be caused to return through duct 37 to the well or receptacle with which the pump is associated.

Thus, it will be seen that I have provided relatively simple and efficient means for diverting pumped water back into the well or for permitting said pumped water to discharge through a screened opening at the forward end of the well spout.

Obviously the details of construction of my improved pump spout may be varied in size, form and arrangement of the various parts without departing from the spirit of the invention the scope of which is set forth in the appended claims.

I claim as my invention:

1. The combination with a pump spout, of adjustable means associated with the discharge end of the spout for causing the pumped water to pass throughout and discharge from said spout or for causing said pumped water to return through said spout to the well or receptacle with which the pump and its spout are associated.

2. The combination with a pump spout, of a duct leading from the discharge opening at the outer end of said spout back through said spout to the interior of the pump with which the spout is associated, and a valve-like member associated with said spout, and operable to cause the pumped water to discharge from the outlet opening at the forward end of said spout, or to return through said duct to the interior of

the pump with which the spout is associated. 65

3. The combination with a pump spout, of a duct leading through the discharge opening of said spout back to the pump with which said spout is associated, and a valve-like member arranged for operation adjacent to the discharge opening in said spout, which valve-like member includes an imperforate plate that is adapted to close the passageway through the return duct, and said valve-like member being provided with 75 a screened opening through which, is adapted to pass, the water that discharges from said pump.

4. The combination, with a relatively fixed pump spout, of manually operable 80 valvular means arranged adjacent to the outer ends of said spout for causing the pumped water to discharge outwardly from said spout or for causing the pumped water to return through the pump spout to the well or receptacle from which it was pumped. 85

5. A pump spout provided with outflow and return ducts and with discharge opening at its outer end, a valve-like member mounted for operation within the outer portion of said spout, and adapted to direct the water passing through the outflow duct to the discharge opening or to direct the water through the outflow duct into said return duct, and said valve-like member being provided with a screened opening that is adapted to register with the discharge opening at the outer end of said spout. 90 95

6. A pump spout having outflow and return ducts, said ducts communicating with each other adjacent to the outer end of the spout, there being a discharge opening formed at the outer end of said spout, and a substantially V-shaped valve member mounted for operation in the forward portion of said spout adjacent to said discharge opening and adapted to direct the flow of water through the outflow duct through said discharge opening or into and through said return duct. 100 105 110

7. A pump spout having outflow and return ducts, said ducts communicating with each other adjacent to the outer end of the spout, there being a discharge opening formed at the outer end of said spout, a 115 substantially V-shaped valve member mounted for operation in the forward portion of said spout adjacent to said discharge opening and adapted to direct the flow of water through the outflow duct through said discharge opening or into and through said return duct, and one of the wings of said V-shaped valve member being provided with a screened opening that is adapted to register with the discharge opening of said 120 125 spout.

In testimony whereof I affix my signature.
CLARENCE C. CHRISMAN.
